GARMENT CLOSURE

Philip H. Robbins, New York, N. Y., assignor to
Poirette Corsets, Inc., New York, N. Y.

Application June 10, 1940, Serial No. 339,803

2 Claims. (CL 2-38)

This invention relates to a garment closure designed primarily for use in connection with the opening in the body of a tight fitting women's undergarment, such as corsets, brassieres and girdles, but it is to be understood that the closure in accordance with this invention is for employment in any connection for which it may be found applicable.

The invention aims to provide, in a manner as hereinafter set forth, a garment closure including means to greatly facilitate the wearer of the garment closing the latter.

The invention further aims to provide, in a manner as hereinafter set forth, a garment closure including means to relieve the pulling action, by the wearer, upon the body of the garment when closing and opening the latter.

The invention further aims to provide, in a manner as hereinafter set forth, a garment closure including an elastic element for facilitating the closing and opening of the garment with which the closure is correlated.

The invention further aims to provide, in a manner as hereinafter set forth, a garment closure including means to overcome the inconvenience, now present in closures of the class to which this invention relates on the operation of the closure to and from closing relation with respect to the opening in the garment.

The invention further aims to provide, in a manner as hereinafter set forth, a garment closure of a form to eliminate the employment therewith of a protecting medium on its inner side for an inner garment or for the body of the wearer when the inner garment is not worn.

The invention further aims to provide, in a manner as hereinafter set forth, a garment closure for enabling the wearer of the garment to quickly connect and disconnect the side walls of the garment opening without inconvenience.

The invention further aims to provide, in a manner as hereinafter set forth, a garment closure of a form to materially reduce the force required of the pull on the garment by the wearer when opening and closing the garment.

The invention further aims to provide, in a manner as hereinafter set forth, a garment closure which is simple in its construction and arrangement, strong, durable, compact, expeditiously and conveniently operated, thoroughly efficient in its use, readily installed with respect to the garment and comparatively inexpensive to manufacture.

Embodying the aims aforesaid and others which may hereinafter appear, the invention

consists of the novel construction, combination and arrangement of parts as will be more specifically described and illustrated in the accompanying drawing, wherein is shown an embodiment of the invention, but it is to be understood that changes, variations and modifications may be resorted to which fall within the scope of the invention as claimed.

In the drawing:

Figure 1 is a fragmentary view in front elevation of a garment showing the adaptation therewith of a closure in accordance with this invention and with the closure partly open.

Figure 2 is a fragmentary view in rear elevation of the structure shown by Figure 1, and

Figure 3 is a section on line 3-3 Figure 1 and with the closure in inactive position.

With reference to the drawing, 5 generally indicates the body of a garment, such by way of example as a corset. The body 5 has a vertical cutout to form an opening 6 to facilitate the positioning of the garment on the wearer. The cutout opens at the top edge of body 5, is closed at its lower end and is of a length materially less than the height of said body 5. The side or lengthwise edges of the opening 6 are indicated at 8, 9. The opening 6 will be of the desired width.

The garment closure, in accordance with this invention, and which will be hereinafter termed a closure structure includes a primary fastener means generally indicated at 10 and a secondary combined fastener and closure means generally indicated at 11. The means 10 is in the form 30 of a pair of normally spaced oppositely disposed sections 12, 13, the section 12 includes a set of spaced hooks 14 and the section 13 includes a set of spaced eyes 15 for correlation with the hooks 14 for detachably connecting the sections 12, 13 together in overlapping relation. The means 11 is of the well known slide fastener type and includes oppositely disposed bendable members 16, 17 of tape-like form, oppositely disposed interengageable fastener elements 18, 19 carried by the members 16, 17 respectively and a slide 20 for correlation with and common to the elements 18, 19 for detachably coupling the members 16, 17 to close the opening 6.

The section 12 includes a bendable fabric strip 50 21 bent upon itself to provide front and rear spaced opposed folds 22, 23 respectively. The fold 22 is of greater cross sectional length than the fold 23 and merges into an inwardly directed fold 24 bearing against the rear face thereof. The fold 23 merges into an inwardly directed

55

fold 25 which opposes in spaced relation the front face thereof. The fold 24 is of greater cross sectional length than the fold 25 and extends outwardly from the latter. Arranged between the folds 22, 23 and extending between the folds 23, 25 is a bendable filler strip 26. Extending between the folds 24, 25 at spaced intervals are the shanks 27 of the hooks 14. The bills 28 of the hooks 14 extend rearwardly, oppose in spaced relation the bend 29 between the folds 23, 25 and overlap in spaced relation the fold 25. The bills 28 of the hooks 14 are spaced inwardly of the bend 30 between the folds 23, 24. The folds 23, 25, filler strip 26, shanks 27 of the hooks 14 and folds 22, 24 are secured together by the stitching 31 disposed lengthwise of section 12. The folds 22, 24 are secured together, in proximity to bend 30 by the stitching 32. The folds 22, 23 and filler strip are secured together, in proximity to the bend 33 by the stitching 34. The filler strip 26 abuts against the inner faces of the bends 29, 33.

The section 13 includes a bendable strip 35 bent upon itself to form an angle-shaped front fold 36 and a flat rear fold 37. The fold 36 merges into an inwardly directed fold 38 arranged against the rear face thereof. The section 13 also includes a flexible strip 39 folded upon itself to form a front fold 40 and a rear fold 41 disposed in opposed relation. The folding of the strip 39 is opposite with respect to the folding of the strip 35. The cross sectional length of the folds 40, 41 is greater than the cross sectional length of the folds 36, 37, 38. The folds 40, 41 are oppositely disposed with respect to the folds 36, 37, 38. Arranged between the folds 40, 41 is a bendable filler strip 42. The fold 40 bears against the rear face of and extends outwardly from the fold 38. The fold 41 bears against the front face of and extends outwardly from the fold 37. Arranged between the folds 38, 40 at spaced intervals are the shanks 43 of the eyes 15. These latter project outwardly from the fold 38. The folds 36, 38, shanks 43 of the eyes 15, filler strip 42 and folds 40, 41 are secured together by the stitching 44. The folds 36, 37 are secured together in proximity to the bend 45 by the stitching 46. The folds 40, 41 are secured together, in proximity to the bend 47 by the stitching 48.

The elements or parts of the sections 12, 13 of the means 10 are non-elastic.

The closure structure includes an oblong base member 49 in the form of an elastic fabric strip 50 of a width and length greater than the width and length of opening 6. The strip 50 is secured, in proximity to its lengthwise edge 51, to the body 5 by the stitching 52 and in proximity to its bottom edge 53 it is also secured to body 5 by the stitching 54. The member 49 constitutes a carrier for the section 13 of the means 10. The section 13 is arranged against one side of and secured to the front face of strip 50 by the stitchings 46 and 48. The stitchings 46 and 48 cause that part of the strip 50, which is arranged between them to be non-elastic to thereby provide base member 49 with a non-elastic portion 55 and an elastic portion 56. The latter is arranged between the stitchings 46 and 52. It is this elastic portion 56 of base member 49 which obtains the objects and advantages as aforesaid of the invention. The strip 50 lengthwise thereof is formed with a pair of oppositely extending folds 57, 58 which abut the front face 59 thereof. The bend 60 relative to the fold 57 aligns with the

bend 47. The stitching 48 is arranged in proximity to the bend 47. The bend relative to the fold 58 forms the edge 51 of member 50. When section 13 of the means 10 is secured to strip 50, the fold 37 bears against the front face 59 of strip 50, aligns in spaced relation with the folds 57, 58, and the fold 41 seats against the front faces of the folds 37, 57.

The flexible member 16 of the means 11 is interposed between the body 5 and the section 12 of the means 10. The member 16 has a portion thereof disposed in outwardly directed relation with respect to the edge or wall 7 of opening 6. The member 16 is secured against the inner face of body 5, in proximity to the said edge 7, by the stitching 61; the latter also secures the member 16 to the folds 22 and 24 of section 12 of means 16. The stitching 32 secures the projecting portion of member 16 to the folds 22, 24. The stitchings 32 and 34 secure the member 16 to the section 12 of the means 10. The bendable member 17 of the means 11 is secured against the fold 53 of the strip 50 and to the inner face of the body 5 by the stitching 53, and it is further secured to the inner face of body 5, in proximity to the edge or wall 8 of opening 6 by the stitching 62. The member 17 has a portion disposed in outwardly directed relation with respect to the said edge 8.

The base member 49 above its lower edge is secured to the members 16, 17 of the means 11 and to the sections 12, 13 of the means 10 by a transverse row of stitching 63. The latter is arranged at the lower ends of the rows of fastener elements 18, 19 carried by the members 16, 17. The material from which the base member 49 is formed is such as to have a very smooth soft rear face which will not be of discomfort to the body of the wearer or injure an inner garment if the latter is worn, under such conditions eliminating the necessity of using a protecting medium on such rear face.

The closure structure as described includes what may be termed a pair of overlapping flaps having coacting interengageable elements, such as hooks and eyes for connecting them together. One of the flaps is inelastic and provided by the section 12 of the means 11. The other of said flaps having an elastic portion and such other flap is provided by the section 13 of the means 11 in connection with the base member 49. The manner of setting up the said pair of flaps provides whereby the said flaps can be initially readily drawn together against a normal strain thereupon when the garment is worn, for fastening the said hooks and eyes. The closure structure as described also includes a pair of overlying flaps arranged one each, over the said other aforesaid pair of flaps, said overlying flaps being provided by the members 16, 17 each carrying a complementary portion of a slide type fastener and adapted when drawn together in closed position, to conceal said first mentioned pair of flaps.

What I claim is:

1. In a closure structure for an opening in the body of a garment, an elongated transversely elastic strip constituting a base member for extension across and for disposing rearwardly of the opening in the garment, a primary fastener means outwardly of said member formed of a front and a rear inelastic section shiftable relative to each other adapted to be normally disposed in spaced overlapping relation and including correlated elements for detachably fastening said sections in overlapping abutting relation to

close said opening when said sections are shifted relatively to each other, means for securing said inelastic rear section to a portion of said base member to form the latter with an inelastic part and an elastic part, a secondary combined fastener and closure means arranged adjacent the said primary means and including a pair of opposed interengageable fastener parts adapted for closing the opening in the garment in addition to and for concealing the said sections in overlapping abutting relation, means for securing one of said parts of said secondary means to said body adjacent an edge of the opening of the latter, means for securing said one part to said front section, means for securing the other of said parts of said secondary means to said body in proximity to another edge of the opening in the body, and means for securing the inner side of the said other part of the elastic part of said base member and to said body.

2. In a closure structure for an opening in the body of a garment, an elongated transversely elastic strip constituting a base member having a rear face with respect to the inner side of the garment and a front face with respect to the outer side of the garment, said member for extension across and for disposing inwardly of such opening and being provided with a pair of op-

positely extending side folds one disposed against a part and the other against another part of said front face, primary fastener means formed of a pair of non-elastic sections including correlated fastener elements for connecting said sections together to close said opening, a secondary fastener means outwardly of said primary means and including a pair of separate portions having correlated means for connecting them together to conceal said primary means, spaced means respectively securing one of said sections against still another portion of said front face and against the front face of one side fold to form said member with an inelastic and an elastic part, means 10 securing the other of said sections to one of said portions, means securing the said one of said portions at one point thereof to said body in proximity to and in extended relation with respect to one edge of said opening, means disposed in proximity to the other edge of said opening for securing the other of said portions in extended relation with respect to the said other edge of the opening, and means for securing the inner side of the said other portion to the garment, to the other fold, to said elastic part and against the outer face of the said other fold.

PHILIP H. ROBBINS.
